COMBINED PRINTING MACHINE AND METER FOR TICKET VALIDATION

Robert C. Ringholz, 436 Court St., San Bernardino, Calif.

Filed July 5, 1963, Ser. No. 75,675

Term of patent 14 years

(Cl. D64—11)

FIG. 1.

FIG. 2.

FIG. 3.

FIGURE 1 is a perspective view taken from the rear and one side of a combined printing machine and meter for ticket validation embodying my new design;

FIGURE 2 is a front elevational view thereof; and

FIGURE 3 is an elevational view thereof taken from the side opposite that shown in FIGURE 1.

I claim:

The ornamental design for a combined printing machine and meter for ticket validation, as shown.
